UNITED STATES PATENT OFFICE.

MELLEN BRAY, OF NEWTON, MASSACHUSETTS.

DEVICE FOR SETTING LACING-STUDS.

SPECIFICATION forming part of Letters Patent No. 329,264, dated October 27, 1885.

Application filed April 29, 1885. Serial No. 163,808. (No model.)

To all whom it may concern:

Be it known that I, MELLEN BRAY, of Newton, in the county of Middlesex and State of Massachusetts, have invented certain new and useful Improvements in Devices for Setting Lacing-Studs, of which the following, taken in connection with the accompanying drawings, is a specification.

My invention relates to devices for setting lacing-studs, and is designed more especially for setting glove-lace studs provided with a concavo-convex washer, such as is described in another application of mine filed in the Patent Office at Washington, District of Columbia, February 14, 1885, and numbered 155,870; and it consists in certain novel constructions, arrangements, and combinations of parts, which will be best understood by reference to the description of the drawings, and to the claims to be hereinafter given.

Figure 1 of the drawings is a side elevation of the stud-setting machine embodying my invention. Fig. 2 is a central vertical section of a portion of the machine through the axis of the setting-tools in position for commencing the setting, with the stud to be set and its washer in position to be acted upon by the descending setting-plunger. Fig. 3 is a similar section of the lower setting-tool with the work thereon and the stud completely set. Fig. 4 is a plan of the lower setting-tool with the work removed, and Fig. 5 is a front elevation of the same. Figs. 2, 3, 4, and 5 are drawn to an enlarged scale.

In the drawings, A is the base of the machine, from which rises the goose-neck A', carrying in its end the setting-plunger B, arranged to be moved upward by a spring, (not shown,) and to be depressed by the lever C, to which motion is imparted by the rod D and a treadle-lever, (not shown,) to which the lower end of said rod is connected, all of which is old and of well-known construction, my present invention being confined to the setting-tools and the means employed to facilitate the insertion of the stud into the pocket for receiving it. In the base of the machine, and in axial line with the setting-plunger B, is set the anvil-socket a, in which is fitted the steel anvil b, having its upper end cupped out to fit the convex outer surface of the stud-head, and ar-

ranged to be slightly adjusted in its socket by means of the screw c, as shown in Figs. 2 and 3. The anvil-socket a has formed upon its upper end the collar a', to which is fitted the cylindrical sleeve d, provided at its upper end with the outwardly-projecting collar d', and at its lower end with the inwardly-projecting annular lip d'', which fits to the body of the anvil-socket below the collar a', as shown in Figs. 2 and 3. The upper end of the sleeve d has formed therein a shallow dovetailed groove, in which is fitted a thin steel plate, e, in the upper face of which is formed the annular curved bottomed recess e', having an inner diameter about equal to the diameter of the base-collar of the stud f to be set, said plate having a portion of its front edge cut away to the inner periphery of said recess, as shown at e'' in Fig. 4, in order that the stud to be set may be slipped upon said plate till its base-collar rests upon its upper surface, with its center or axis concentric with said annular recess e', while the outer head of the stud is beneath the plate e and resting in the concave end of the anvil b, as shown in Figs. 2 and 3. The plate e is made of a thickness just equal to the desired distance between the outer head and the base-collar of the stud, and the sleeve d is forced downward, so as to clamp the outer head of the stud f between the cupped end of the anvil b and the under side of the plate e by the tension of the coiled spring g, surrounding the body of the anvil-socket a between its collar a' and the annular lip d'' of the sleeve d, as shown in Figs. 2 and 3.

In order to place the stud f upon the plate e in the proper position to be set, the sleeve d and plate e must be lifted against the tension of the spring g, which may be done by pressing upon the rear end of the lever E, pivoted at h to the goose-neck A', and having its front end forked, so as to engage with the collar d' upon two opposite sides of said sleeve. The upper end of the sleeve d has a recess, d'', formed in its front side to facilitate the insertion of the stud to its proper position upon the plate e and its removal after being set. By this construction and arrangement of the anvil and its accessories for holding the stud in position thereon a solid bearing for the stud is obtained to receive the blow of the

clutching-tool, the outer surface of the head resting in the cupped upper end of the anvil *b*, and the plate *e* filling the space between said head and the base-collar, so that when the blow of the clutching-tool is given to the shank of the rivet to clutch it the blow is transmitted through the stud to the anvil *b*, no strain being applied to the plate *e*, except a crushing strain.

10 Heretofore, as far as I know, in setting studs having solid heads the whole strain of clutching the shank of the stud—and that a tensile strain—has been received by the plate which entered between the outer head and the base-collar, which has been found to be objectionable, particularly when setting studs designed to be used with a lacing cord of small size, as for glove-lacings, for the reason that the plate could not be made sufficiently strong to resist 20 the strain for any considerable time, which objection is entirely overcome by my invention. Another advantage of this arrangement is that if from any cause the space between the outer head and base-collar of the stud is 25 too great, the act of setting the stud reduces said space to the required standard dimension, and uniform with all the studs set upon the same plate.

It is obvious that a thicker or thinner plate 30 may be substituted for the plate *e* shown in the drawings, according to the size and style of stud to be set, with which change and a proper adjustment of the anvil *b* by the screw *c* my improvement, so far as described, is 35 adapted to set the ordinary tubular-shanked lacing-stud; but in order to facilitate the setting of my improved glove-lace hook or stud with its concavo-convex washer, which forms the subject-matter of another application, filed 40 February 14, 1885, Serial No. 155,870, I attach to the clutching-tool *i* the sleeve *j*, arranged to surround and project below the lower end of the clutching-tool *i*, and to be moved upward thereon against the tension of 45 the spring *k*, said sleeve being guided in its vertical movements and prevented from turning upon its axis by the pins *l*, projecting radially from the enlarged part of the clutching-tool *i* through slots *m*, cut through the 50 walls of the sleeve *j*, all as shown in Fig. 2. When the stud has been placed in position upon the plate *e* with its shank upward, and the material in which the stud is to be set and the concavo convex washer *n* are placed upon 55 the shank, as shown in Fig. 2, if the setting plunger be moved downward, the sleeve *j* first comes in contact with the washer *n* and forces it downward into close contact with the material and the material into close contact with 60 the base-collar, and by virtue of the concave form of the side of the washer *n*, which is next to the material, the material is bent down around said base-collar and into the annular

recess *c'*, as shown in Fig. 2, and then the clutching-tool *i* descends and clinches the 65 shank over upon said washer, while the sleeve *j* remains stationary.

When it is desired to set studs without the concavo-convex washer, the annular recess *c'* may be dispensed with, the plate *e* having its 70 upper side made a plain flat surface like its under side.

What I claim as new, and desire to secure by Letters Patent of the United States, is—

1. As a means for holding a lacing-stud while 75 being set and receiving the blow of the setting-tool, a stationary anvil having its upper end shaped to fit the outer surface of the head of the lacing-stud, in combination with a plate arranged above said anvil and adapted to fill 80 the space between the outer head and the base-collar of the stud to be set, and a spring arranged to act upon and press said plate toward said anvil to clamp the head of the stud between it and said anvil, so that the shock of 85 the blow of the clutching-plunger shall be transmitted to the stationary anvil instead of being received and sustained by said plate, substantially as described.

2. The combination of a stationary anvil 90 having its upper surface shaped to fit the outer surface of the outer head of the stud to be set, a sleeve surrounding said anvil, a removable plate secured to and extending across the top of said sleeve and arranged to fill the space 95 between said outer head and the base-collar of said stud, and a spring arranged to press said sleeve and plate downward so as to clamp the head of the stud between said plate and anvil, substantially as described. 100

3. The combination of the stationary anvil *a* *b*, the sleeve *d*, arranged to surround the anvil, and provided with the recess *d'*, the plate *e*, secured to the upper end of the sleeve *d*, and provided with the recess *c'* and the notch *c''*, and the spring *g*, all arranged and adapted to operate substantially as and for the purposes described. 105

4. The combination of the anvil *a* *b*, the sleeve *d*, provided with the collar *d'*, the plate *e*, secured to said sleeve, the spring *g*, and the lever *E*, all arranged and adapted to operate substantially as described. 110

5. The combination of the anvil *a* *b*, the sleeve *d*, the plate *e*, the spring *g*, the clutching-tool *i*, the sleeve *j*, and the spring *k*, and mechanism, as described, for imparting to said clutching-tool a reciprocating motion, substantially as described. 115

In testimony whereof I have signed my name 120 to this specification in the presence of two subscribing witnesses.

MELLEN BRAY.
